SOLE-SHAPING MACHINE

Leon D. Alderman, Magnolia, Mass., assignor to
 United Shoe Machinery Corporation, Flemington, N. J., a corporation of New Jersey

Application June 14, 1951, Serial No. 231,566

8 Claims. (Cl. 12—21)

1

This invention relates to machines for shaping unattached soles and more especially to improvements in sole shaping machines of the type in which a work-piece is interposed between relatively movable molding members to receive their forming pressure. Although the invention is hereinafter illustrated as applied to sole molding, it will be recognized that the invention may well be applicable also to machines for molding other parts of shoes and other objects.

The importance of accurately registering a sole, especially its ball line, with respect to cooperative pressure-applying molds has hitherto been recognized and dealt with, for example, as disclosed in United States Letters Patent No. 2,065,465, granted December 22, 1936, upon application of J. M. Whelton, No. 2,306,430, granted December 29, 1942, upon application of A. Eppler, Jr., and No. 2,323,933, granted July 13, 1943, upon application of E. N. Preble. A common practice as disclosed there and elsewhere is to employ edge engaging devices to move a sole widthwise and lengthwise as may be required predeterminedly to position it relatively to the mold contours. For actuating such positioning devices in relation to different shapes and sizes of soles, for clearing these devices from the path of the movable mold prior to the shaping operation, and for thereafter arranging the sole-locating mechanism in readiness to receive the blank next to be formed, various means have been proposed which have limited the productivity of the operator because they have generally been of rather complex organization and/or required the exercise of considerable dexterity by him.

In view of the foregoing, it is an object of the present invention to provide in a sole-shaping machine of the type employing pressure-applying molds improved and automatic gaging mechanism of simple construction by which a sole may be easily and quickly located and held in proper position for molding.

To the accomplishment of this objective, and in accordance with one feature of the invention, there is provided in a sole-shaping machine the novel combination with a pair of molds, one of which is movable toward the other for applying shaping pressure, a flexible blanket extending between said molds to support a sole for the shaping operation, sole-locating members, means operative at the beginning of movement of said one of said molds toward the other for operating said sole-locating members to position said sole in predetermined relation to said molds, and

2

means operative during continued movement of said one of said molds toward the other for retracting said locating members.

A further feature of the invention resides in the provision in such a sole-shaping machine of means automatically effective to clamp the sole against the blanket prior to the retractive movement of the sole-locating members whereby lateral displacement of the sole relatively to the mold is avoided.

The above and other features of the invention, together with novel combinations of parts, will now be more fully described in connection with the accompanying drawings of an illustrative machine in which the invention is embodied.

In the drawings,

Fig. 1 is a plan view of the lower mold showing associated sole-locating devices both in and out of sole edge engaging positions;

Fig. 2 is a view in side elevation of the elements seen in Fig. 1;

Fig. 3 is a section taken along the line III—III of Fig. 1; and

Fig. 4 is a longitudinal section omitting portions of the machine but showing the upper and lower molds and associated parts in operative positions with respect to a sole.

In certain respects the machine organization embodying the present invention and selected for purposes of illustration may be similar to the disclosures made in the above-mentioned patents and, accordingly, only such portions of the machine as it is necessary particularly to refer to for an understanding of the invention are herein shown and will be described in detail.

The illustrative machine comprises a stationary upper mold 10 (Fig. 4) and a cooperative lower complementary mold 12 that is movable heightwise toward and from sole-molding position by appropriate power means, only a portion 11 (Fig. 4) of which is shown, and not forming a part of this invention. The mold 12, of rubber or other suitable material, supports a resilient pad 14 and is carried on a flat, vertically movable crosshead 16 to which upright mold-retaining side walls 18, 18 and end walls 20, 20 (Fig. 4) are secured.

For supporting a sole S to be shaped by the pressure-applying molds 10 and 12, a flexible blanket 22 extends between them and has its ends respectively anchored by screws 24 (Figs. 1 and 4) threaded into clamping members 26, each of which is pivotally supported by a cross pin 28. The pins 28, 28 respectively extend horizontally

and widthwise between the ends of corresponding upper arms of composite bell cranks 30 and 32 (Figs. 2 and 4) arranged at opposite ends of the walls 18, 18. The arms of the bell cranks 30, 32 are adjustably secured to, and supported by, pivot studs 34, 36 respectively, the latter being journaled in the walls 18. The lower arms of the bell cranks 30, 32 are connected by a tension spring 38 suitable to hold the blanket 22 in taut condition when initially receiving a sole to be shaped but yieldable to permit equal and opposite angular turning movement of the bell cranks 30, 32 upon cooperative action of the molds 10 and 12.

The gaging means provided for automatically locating a sole S on the blanket 22 comprise sole edge engaging members including a toe abutment 40, a heel abutment 42, a pair of side gage jaws 44, and a pair of heel portion gage jaws 46, all mounted for effective cooperation with cam-actuating mechanism as will hereinafter be described. The respective abutments 40, 42 are affixed to horizontally projecting pairs of arms 48, 50. The latter are spaced widthwise near the opposite extremities of the blanket 22 and respectively supported by studs 52, 54 secured respectively to the upper ends of upright arms of bell cranks 56, 58. These bell cranks 56, 58 are carried up and down with the mold 12, being pivotally supported on bearings 60, 62 respectively, affixed to the lower portion of bracket 70. In order to effect appropriate centering of the sole S lengthwise of the blanket 22 and with respect to the mold 12, horizontal arms 64, 66 of the bell cranks 56, 58, respectively, are articulated, an end of the arm 66 being forked and bored to carry a pin 68 which is slidable in a slot formed in the adjacent end of the arm 64.

The pairs of side and heel portion gage jaws 44, 46 are mounted in a manner somewhat similar to that disclosed in the Epler and Whelton patents above referred to. Adjustable lengthwise by tongue and groove connection with the side wall 18 is the bracket 70 for supporting the gage jaws, bolts 72 extending through slots 74 (Fig. 2) in the lower portions of the bracket and being threaded into the walls 18. A horizontal plate 76 bolted to a transversely extending upper portion 78 of the bracket 70 affords support for the two pairs of jaws 44 and 46. Each of these pairs consists of two horizontally disposed jaws located one at either side of the mold 12 and provided with inwardly curved portions 80, 81 respectively (Fig. 1). Each portion 80 terminates in an upright inclined conical finger 82 and a depending roll 84 suitable for engaging a sole edge, the fingers 82 aiding an operator in easily spotting a sole approximately into position on the blanket 22. At the ends remote from the rolls 84 the side gage jaws 44 are pivotally mounted upon individual fulcrum studs 45. The jaws 44 are urged toward sole edge engaging positions by means of a compression spring 88 (Fig. 1), the opposite ends of which bear against ears 90 projecting beyond the pivoted ends of the jaws 44. The spring 88 is supported by a rod 92 extending through the convolutions of the spring and through holes in the ears 90, the rod 92 being held in place by a head 94 at one end and a nut 96 at the other. The portions 81 of the heel portion gage jaws 46 respectively terminate in inclined lips 98 cooperative to guide the heel end of a sole being deposited and respectively support a depending roll 100 for contacting opposite side edges of such heel portion. The heel portion gage jaws 46 are pivotally mounted on fulcrum studs 102 and are

interconnected by a tension spring 104 that urges the jaws 46 toward sole-engaging positions.

Each pair of gage jaws 44, 46 are connected in articulated relation by means which communicate angular motion from one jaw to the other and equalize movements of the jaws to enable them to centralize a sole widthwise on the blanket 22. The side gage jaws 44 are interconnected by arms 106 (Fig. 1) formed as bell-crank extensions of the jaws and having ends disposed in overlapping relation, a pin 108 carried by one of the arms being slidably received within a slot 110 in the other arm. The heel portion gage jaws 46 are similarly articulated by bell-crank extensions or arms 112, one of which carries a pin 114 which extends through a slot 116 in the other arm.

For actuating the sole-locating means automatically on heightwise movement of the mold 12 a pair of stationary, vertical posts 120 is provided to one of which there is adjustably secured by bolts 122 a pair of clamping brackets 124, 126. To the latter is bolted a longitudinally adjustable plate 128 having V-shaped face cams 130, 132 respectively formed in opposite upright portions 134, 136 thereof. A cam roll 138 is rotatably mounted on the bell crank 56 and is arranged to cooperate with the cam 132 for actuating the abutments 40, 42, the upper bell-crank arms 56, 58 being yieldingly urged toward one another by a tension spring 140. For actuating the heel portion and side gage jaws 46, 44 the cam 130 in the upright portion 134 (Fig. 3) cooperates with a cam roll 142 rotatably mounted on a lever 144 pivotally mounted at its lower end on a pivot stud 146 carried by a lateral projection of the bracket 70. Engagement of the cam roll 142 and the cam 130 is urged by linkage now to be described. A ball-ended stud 150 is threaded into the upper end of the lever 144 and has socket connection with one end of a link 152. The other end of the latter has a socket connection with a ball-ended pin 154 threaded into one of the heel portion gage jaws 81. The tension spring 104 is by this means enabled to maintain effective relation between the cam roll 142 and the cam 130. The pin 154 bears on the inner side of the side gage jaw portion 80 as does a corresponding pin 156 (Figs. 1 and 3) bear on the inner side of the other side gage jaw portion 80 to assure simultaneous sidewise retraction of both sets of jaws during upward movement of the lower mold 12.

An arm 158 bolted to the plate 128 has a notch 160 (Fig. 2) for receiving and registering a projection 162 of the bracket 70. This arrangement is to assure that proper relationship is maintained between the cooperative cams and cam rolls above mentioned even though several adjustments in their respective positions may be necessitated by different operating conditions.

To assure that a sole, once located on a horizontal blanket 22 by operation of the sole edge engaging members as will be described, will not thereafter be skewed, creep, or otherwise move from its initially predetermined position relative to the molds when the sole-locating members are retracted to permit application of molding pressure, means are provided which become operative during continued movement of the mold 12 toward the mold 10 to clamp the located sole against the blanket 22. For this purpose the crosshead 16 (Fig. 4) is adapted to receive the upper end of a vertical tubular casting or sleeve 164, bolts 166 extending through

a flange on the latter and being threaded into the crosshead. A plunger 168 is yieldingly mounted in the sleeve 164 for relative axial movement, a compression spring 170 surrounding the lower portion of the plunger 168 and having its ends respectively abutting a collar 172 of the plunger and a cap 174 adjustably threaded on the lower end of the sleeve 164. When the machine is in inoperative condition a reduced upper portion 176 of the plunger 168 extends through the crosshead 16, the mold 12 and the pad 14 and has a hollow extremity to receive and support a rubber plug 178 (Fig. 2) for contact with that area of the horizontal blanket 22 in juxtaposition with the ball line of the sole to be molded.

In operating the machine a sole S is placed on the blanket 22 as indicated in Figs. 1 and 2. The bolts 72 will have been adjustably fixed with respect to the slots 14 so that the bracket 70 correctly supports the sole abutments 40, 42 and engaging rolls 84 and 100 lengthwise of the soles to be molded. The plate 128 also will have been so adjusted longitudinally that its cams 130, 132 and corresponding upright portions 134, 136 will respectively control an appropriate range of centralizing locating movements of both the side and heel portion gage jaws 44, 46 and the toe and heel abutments 40, 42 for the soles to be formed. As the mold 12 begins its upward movement, the cam roll 138 cooperates with the stationary cam 132 and the abutments 40, 42 respectively engage the toe and heel edges to locate the sole lengthwise on the blanket. Under the tension of the spring 140 it will be seen that the abutments 40, 42 will move together to position the ball line of a sole lengthwise of the blanket 22 so that the ball line of the sole will be in predetermined relation lengthwise of the molds irrespective of the length of the sole. The cam 130, being higher than the cam 132 on the plate 128, next cooperates with its cam roll 142 to permit the jaws 44, 46 to be actuated into sole edge engaging positions for locating the sole widthwise. Having moved inwardly as far as the cam 132 and/or the sole edge will permit, the abutments 40, 42 have completed their sole-locating function and are then automatically cleared from the path of the mold 12 by its continued upward movement. This is effected by the cam roll 138 being carried into engagement with the upper wall of the cam 132. Similarly, having moved inwardly as far as the cam 130 and/or the sole edge will permit, the gage jaws 44, 46 complete their widthwise sole-locating function and are automatically cleared from the path of the mold 12, the cam roll 142 engaging the upper portion of the cam 130. It may be noted that regardless of the effectiveness of the cam action in this respect, the upper mold 10, upon engaging the upwardly moving inclined surfaces of the fingers 82 and lips 98, will move them sidewise and away from the sole. When the sole-locating gages are about to be thus retracted, the molds 10 and 12 commence to cooperate to form the sole as indicated in Fig. 4, the plug 178 clamping the sole in position between the blanket and the mold 10 to hold the sole against displacement, the plug being yieldingly depressed against the resistance of the spring 170 until the top of the plug 178 is even with the under side of the blanket at the ball line as shown. As the molds 10 and 12 come together the blanket 22 yieldingly conforms to their sole-pressing faces, the bell cranks 30, 32

swinging in opposite directions against the resistance offered by the spring 38.

On lowering the mold 12 to its initial position, the blanket 22 is returned to taut horizontal condition by the spring 38 and the retracted gages 44, 46 and abutments 40, 42 are ready to position the next sole to be shaped.

Having thus described my invention, what I claim as new and desire to secure by Letters Patent of the United States is:

1. In a sole-shaping machine, a pair of molds for applying shaping pressure to a sole placed therebetween, one of said molds being movable toward the other to apply pressure to the sole, means for supporting the sole between the molds, sole-locating members, means operative at the beginning of movement of said one of said molds toward the other for operating said sole locating members to position said sole in predetermined relation to said molds, and means operative during continued movement of said one of said molds toward the other for retracting said sole-locating members.
2. In a sole-shaping machine, a pair of molds for applying shaping pressure to a sole placed therebetween, one of said molds being movable toward the other to apply pressure to the sole, means for supporting the sole between the molds, sole-locating members, and means operative at the beginning of movement of said one of said molds toward the other for operating said sole locating members to position said sole lengthwise with respect to said molds so that the ball line of the sole will be in predetermined relation to said molds irrespective of the length of the sole.
3. In a sole-shaping machine, a pair of molds for applying shaping pressure to a sole placed therebetween, one of said molds being movable toward the other to apply pressure to the sole, means for supporting the sole between the molds, sole-locating members, means operative at the beginning of movement of said one of said molds toward the other for operating said sole locating members to position said sole lengthwise with respect to said molds so that the ball line of the sole will be in predetermined relation to said molds irrespective of the length of the sole, and means operative during continued movement of said one of said molds toward the other for retracting said sole-locating members.
4. In a sole-shaping machine, upper and lower molds, one of said molds being movable toward the other to shape a sole placed therebetween, a flexible blanket extending between said molds to support a sole for the shaping operation, sole-locating members, means operative at the beginning of movement of said one of said molds toward the other for operating said sole-locating members to position said sole in predetermined relation to said molds, and means operative during continued movement of said one of said molds toward the other for retracting said sole-locating members.
5. In a sole-shaping machine, upper and lower molds, one of said molds being movable toward the other to shape a sole placed therebetween, a flexible blanket extending between said molds to support a sole for the shaping operation, sole-locating members, means operative at the beginning of movement of said one of said molds toward the other for operating said sole-locating members to position said sole in predetermined relation to said molds, means operative during continued movement of said one of said molds toward the other for retracting said sole-locating members.

molds toward the other for retracting said locating members, and means cooperating with one of said molds for clamping the blanket and the sole together prior to the retractive movement of said sole-locating members.

6. In a sole-shaping machine, upper and lower molds, one of said molds being movable toward the other to shape a sole placed therebetween, a flexible blanket extending between said molds to support a sole for the shaping operation, sole-locating members, and means operative at the beginning of movement of said one of said molds toward the other for operating said sole-locating members to position said sole lengthwise of said blanket so that the ball line of the sole will be in predetermined relation lengthwise of the molds irrespective of the length of the sole.

7. In a sole-shaping machine, upper and lower molds, one of said molds being movable toward the other to shape a sole placed therebetween, a flexible blanket extending between said molds to support a sole for the shaping operation, sole-locating members, means operative at the beginning of movement of said one of said molds toward the other for operating said sole-locating members to position said sole lengthwise of

5 10 15 20 25

said blanket so that the ball line of the sole will be in predetermined relation lengthwise of the molds irrespective of the length of the sole, and means operative during continued movement of said one of said molds toward the other for retracting said sole-locating members.

8. In a sole-shaping machine, upper and lower molds, one of said molds being movable toward the other to shape a sole placed therebetween, a flexible blanket extending between said molds to support a sole for the shaping operation, sole-locating members, means operative at the beginning of movement of said one of said molds toward the other for operating said sole-locating members to position said sole lengthwise of said blanket so that the ball line of the sole will be in predetermined relation lengthwise of the molds irrespective of the length of the sole, means operative during continued movement of said one of said molds toward the other and cooperating with one of said molds for clamping the blanket and the sole together, and means for thereafter retracting said sole-locating members.

LEON D. ALDERMAN.
